United States Patent Office.

E. H. OLMSTEAD, OF SAVANNAH, GEORGIA.

Letters Patent No. 67,572, dated August 6, 1867.

IMPROVED RAILWAY-CAR SEAT.

The Schedule referred to in these Letters Patent and making part of the same.

TO ALL WHOM IT MAY CONCERN:

Be it known that I, E. H. OLMSTEAD, of Savannah, Chatham county, Georgia, have invented a new and useful Improvement in Seats for Railroad Cars; and I do hereby declare that the following is a full, clear, and exact description thereof, which will enable others skilled in the art to make and use the same, reference being had to the accompanying drawings, forming part of this specification.

The object of this invention consists in constructing the seats in such a manner that they may, by being reversed, be converted into a lounge or bed, and which will be understood from the following:

Figure 1 represents a side elevation of my improved car-seat as converted into a bed.

Figure 2 shows side elevation of the same as used for a seat.

Similar letters of reference indicate corresponding parts.
a represents the seat, which is hinged to the frame b. The arms of the seat are cut away sufficiently at c so as to allow them to pass each other without touching when folding the same. When these seats are turned over in order to use them as a couch, the arms resting on the floor of the car will act as legs to support the same.

I claim as new, and desire to secure by Letters Patent—

The construction and arrangement of the arms of the seat, as at c, when said seat is hinged and adjusted in the manner and for the purpose herein described.

E. H. OLMSTEAD.
